PANEL UPHOLSTERING MACHINE AND
METHOD

Allister S. Mitchell, Detroit, Mich., assignor to
National Automotive Fibres, Inc., Detroit, Mich.,
a corporation of Delaware

Application March 16, 1935, Serial No. 11,527

25 Claims. (Cl. 154—41)

This invention relates to a panel-upholstering method and a novel machine for conveniently practicing said method.

The primary object of the invention is to improve and cheapen the upholstering of panels.

The invention finds an extremely important application to the purpose of upholstering panels which are adapted for use in lining or other walls of automobile bodies. It is now familiar practice to apply such trim-panels by means of suitable fasteners, such as snap-buttons or other snap-fasteners.

The invention is illustrated, in a preferred embodiment, in the accompanying drawings, in which—

Figure 1 is a broken elevational view of a machine for conveniently practicing the method; Fig. 2, a plan view of the same with a panel and fabric (shown brokenly) in position thereon; Fig. 3, a broken sectional view of a part of the mechanism for tilting the panel-support, taken as indicated at line 3 of Fig. 5; Fig. 4, a broken sectional view taken as indicated at line 4 of Fig. 2; Fig. 5, a broken sectional elevational view taken as indicated at line 5 of Fig. 2; Fig. 6, a broken sectional view of the suction box and panel-supporting member; Fig. 7, a similar view with the panel-support in its lowermost position; Fig. 8, a plan view of a panel, such as the left rear door panel for an automobile, adapted to be upholstered in accordance with the present invention; and Fig. 9, a bottom plan view of the panel shown in Fig. 8 after the upholstery has been attached.

In the drawings, A designates a frame adapted to support on its upper side a suction box A'; B, a panel-supporting member equipped on its upper side with a panel-supporting plate B'; and C, mechanism for actuating the panel-supporting member B and panel-support tilting mechanism C'.

The frame A may be of any suitable construction and is shown with suitable legs 10 which support a bed 11 to which is secured the suction box A' by means of bolts 12. The suction box A' comprises a box-like structure connected at its lower side to a suction elbow 13 through which air may be drawn by means of a suitable blower, not shown, to produce a partial vacuum in the box. The lower side of the box is perforated to permit a plunger 14 of the member B to be projected therethrough and a suitable stuffing box 15 is provided to furnish a substantially air-tight connection. The upper face 16 of the suction box is perforated, as indicated at 17, and serves to admit air from around the edges of the panel-

supporting plate B' when the member B is in its extended position. When the member B is in its lowermost position, as shown in Fig. 7, the plate B' forms a closure for the opening 17. The suction-box A' is further provided with a perimetral frame 18 which conforms to the outline of the plate B' but lies slightly beyond the same when the plate is in its lowermost position.

The panel-supporting member B comprises the plunger 14 mentioned above and is equipped at its upper end with a rigidly connected head 19 to which the panel-supporting plate B' is pivotally connected, as indicated at 20. To the plunger 14 is rigidly connected a valve disc 21 which forms a closure for the opening 17 when the plunger is in its extended position, as shown in Figs. 1 and 5. The plunger 14 is hollow, with its upper portion blocked off by a plug 22. A port 23 communicates with the interior of the suction-box A' so that the upper end-portion of the plunger is subjected to a vacuum corresponding with that in the suction-box A'. The lower portion of the plunger operates through a suitable guide-member 24 provided on the frame A and is equipped near its central portion with a roller 25 adapted to rest on the elevating-member 26, as will be explained below. A foot-treadle 27 is pivoted to the frame at 28 and has a rearwardly extending arm 29 which is adapted to engage the lower end of the plunger and elevate the same independently of the mechanism C. The treadle is normally held in its inoperative position by means of a tension spring 30.

The panel-supporting plate B' is fixed to a base member 31 and is provided near its central portion with a suctional area 32 which communicates with the passage 33 in the hollow upper end of the plunger 14. Thus it will be understood that when a panel is placed on the plate B', its central portion may be gripped firmly against the plate through the action of the suction in the box A'. When the plunger is retracted into its lowermost position, the opening 17 in the top of the suction-box will be uncovered by the valve member 21 and the marginal edges 34 of a superposed fabric 35 will be drawn inwardly around the panel 36 and will be pressed against the lower side of said panel by contact with the perimetral frame 18, see Figs. 6 and 7.

The plunger member 14 is raised and lowered in the timed cycle by means of the mechanism C, which comprises a motor 37 mounted on a horizontal support 38 secured to the frame A by means of bolts 39. A cam shaft 40, journaled in brackets 41, is driven by the motor through suitable worm gears contained in the gear box 42. A

centrally disposed cam 43 is engaged by a roller 44 journaled on the arm 26 which is pivotally connected to the frame A at 45. Thus it will be understood that for each complete revolution 5 of the shaft 40, the plunger 14 will be raised and lowered once. In order to tip-up the panel-support B' and assist the action of the vacuum in drawing the edges of the fabric around the panel 36, a pair of push rods 46 are provided and extend upwardly through the stuffing boxes 47 in the suction-box A' to contact the lower side of the panel-support B'. As shown in Fig. 3, the lower ends of the rods 46 extend through sleeves 48 and make a yielding connection by means of 10 a spring 49 with a yoke 50 provided with a roller 51 which rides on a rock arm 52 pivoted to the frame at 53 and makes a driving connection with a cam 54 by means of a roller 55. The sleeve 48 is free to slide upwardly and downwardly through 15 a bushing 56 provided in the bracket 57 secured to the frame of the machine. The cams 54 are timed with respect to the cam 43 so that the push rods 46 will project up into engagement with the panel-support on its downward movement to permit one side of the panel 36 to come into engagement with the frame 18 while the opposite side is 20 still in the air, as shown in Fig. 6. The push rod 46 is then retracted and the panel settles down into the position shown in Fig. 7.

25 The panel-supporting plate 36 may be slightly concave upwardly, as shown in Fig. 6, or, if desired, it may be made sufficiently flexible that when it is in its lowermost position, as shown in Fig. 7, the panel plate will be bent concave upwardly. As the suction which is applied by the 30 suctional area 32 holds the panel 36 snugly against its face, it will be warped with its marginal edges turned upwardly while the superposed fabric 35 will be drawn taut between the 35 upturned marginal edges of the panel. Thus it will be understood that after the fabric has been secured in position by suitable adhesive and the panel elevated above the suction-box A', the panel will return to its original straight 40 confirmation and stretch the upholstery 35 tightly across its face.

45 Ordinarily, the panel 36 is provided with one or more perforations 58 to receive window handles, or the like. In order to fit the fabric 50 snugly around these openings, holes are cut there-in and suitable flaps 59 are provided, see Fig. 9, and said flaps are drawn through the openings and pressed against the underside of the panel by suitable spacing pads 60, see Fig. 4, which are 55 secured to the top wall 16 of the suction-box by means of machine screws 61.

60 The method of upholstering the panel is practiced by allowing the continuously driven motor 37 to raise the plunger 14 to its uppermost position and placing a panel 36 in proper superposed position upon the panel-support B'. A suitably shaped piece of upholstery 36 is then placed on top of the panel; as shown in Fig. 2; and glue or 65 other adhesive is applied to the bottom outer marginal portions of the panel 36 and the fabric 35. The motor then permits the plunger 14 to slide downwardly on the arm 26 and suction is applied to the bottom side of the panel by the suction-box A' through the opening 17 which is 70 uncovered by the plate 21. The push rods 46 tilt the plate B' and the suction draws the marginal edges 34 tightly around the panel 36. The push rods then permit the panel to settle into the position 75 shown in Fig. 7 and the marginal edges of the fabric are pressed snugly against the panel

which has been warped out of shape by being drawn against the concave panel-support B'. The speed of the shaft 40 is such that the panel remains in the position shown in Fig. 7 a sufficient length of time to assure a tight connection between the panel and fabric which is then raised into the original position where the upholstered panel may be removed and replaced by the next panel. It will be understood that during the above steps, the underside of the flaps 59 and 5 adjacent portions of the panel will also be coated with adhesive and joined in the same manner. In case the operator wishes to delay the retraction of the plunger 14 or wishes to operate the machine without power, he can raise the panel- 10 support at will by means of the treadle 27, as will be readily understood.

15 In operating the machine, it has been found that where a suitable adhesive such as latex is used, from three to five panels may be completed 20 in a minute. A vacuum of several pounds drawing air around the adhesive causes it to dry very quickly. The adhesive may be brushed on or sprayed, as desired.

25 By tilting the plate on its downward travel, one edge of the fabric is gripped securely and the operator may help to smooth out the other edges without getting the material out of position.

30 The foregoing detailed description has been given for clearness of understanding only, and no unnecessary limitations should be understood therefrom, but the appended claims should be construed as broadly as permissible, in view of the prior art.

35 What I claim as new, and desire to secure by Letters Patent, is:

1. In a panel-upholstering machine: a panel-support adapted to support a panel with its edge-portions projecting and upholstery-fabric with edge-portions projecting beyond the panel; and 40 means for applying suction to draw the margins of the fabric under the margins of the panel.

2. In a panel-upholstering machine: a panel-support adapted to support a panel and superposed fabric with projecting margins; a suction-box having a bearing for the margin of the panel and interposed fabric-margin; means for effecting relative approaching and receding movements of said panel-support and suction-box; and means for applying suction through said 50 suction-box whereby the margins of the fabric will be drawn beneath the margins of the panel as said panel and said bearing approach each other.

3. A panel-upholstering machine comprising: a panel-support adapted to support a panel with projecting margins and superposed fabric having projecting margins; a suction-box beneath said panel-support; and means for causing relative movement of the panel-support and suction-box and applying suction to draw the margins of the fabric between the suction-box and the margins of the panel.

4. A device as specified in claim 3, including means for tilting the panel-support relative to the suction-box as they approach each other so that one margin of the fabric will be folded about an edge-portion of the panel and pressed against the suction-box in advance of the pressing action at the opposite margin of the fabric.

5. A device as specified in claim 3, including means for pressing the inturned marginal portions of the fabric against the panel.

6. A device as specified in claim 3, including means for flexing the marginal portions of the

- panel upwardly towards the fabric and means for pressing the marginal portions of the fabric against the lower side of said flexed panel.
7. In a machine of the character set forth: a frame; a suction-box mounted on said frame and having an opening in its upper side; a panel-support disposed over said opening and adapted when lowered to form a closure therefor, said panel-support being spaced above the upper surface of said suction-box when at the upper end of its traverse; and means for raising and lowering said panel-support.
8. A machine as specified in claim 7, in which the panel-support is mounted upon a plunger adapted to be projected from the suction-box through said opening, and said plunger is provided with means for closing said opening when the panel support is projected to its uppermost position.
- 20 9. In a machine of the character set forth: a frame; a suction-box mounted on said frame and having an opening in its upper side; a plunger adapted to be projected through said opening; a panel-support mounted on the upper end of said plunger and adapted in its lowermost position to form a closure for said opening and in its uppermost position spaced at a distance above the top of said suction-box; a closure member mounted on said plunger within said suction-box so as to 30 close said opening when the plunger is in extended position; and means for raising and lowering said plunger.
10. A machine as specified in claim 9, in which the panel-support is pivotally mounted on the plunger, and means are provided for tilting said panel-support while it is being raised or lowered.
11. In a machine of the character set forth: a frame; a suction-box mounted on said frame and having an opening in its upper side; a plunger adapted to be projected through said opening; a panel-support pivotally mounted on the upper end of said plunger and adapted to form a closure for said opening; means for raising and lowering said plunger; and means for tilting said panel-support with respect to the suction-box in timed relation to the movement of said plunger.
12. In a machine of the character set forth: a frame; a suction-box mounted on said frame and having an opening in its upper side; a plunger adapted to be projected through said opening; a panel-support pivotally mounted on the upper end of said plunger and adapted to form a closure for said opening; and a motor-driven shaft provided with cam-means for raising and lowering said plunger, and an additional cam and push rod adapted to tilt said panel-support in timed relation to the movement of said plunger.
13. In a machine of the character set forth: a frame; a suction-box mounted on said frame and having an opening in its upper side; a plunger adapted to be projected through said opening; a panel-support mounted on the upper end of said plunger and spaced above the top of said suction-box when raised and adapted to form a closure for said opening when lowered, said panel-support having in its upper face a suction area adapted to grip a panel resting thereon, and said area communicating through a passage in said plunger with the interior of the suction-box, said suction-box having a top-surface adapted to form a bearing for the margin of the panel when lowered; and means for lowering said panel-support to cause the margins of the panel board to seat on said bearing and the central portion of 70 the panel-board to be bowed downwardly.
14. A panel-upholstering method which comprises; supporting a panel and a fabric thereon with margins projecting beyond the edges of the panel; and suctionally folding the fabric-margins about and beneath the edge-portions of the panel. 5
15. A panel-upholstering method which comprises: supporting a panel with its margins projecting and fabric thereon with the fabric marginal portions projecting beyond the panel; suctionally drawing the fabric edge-portions about 10 and beneath the edge-portions of the panel; and pressing the fabric margins onto the lower margin of said panel.
16. A panel-upholstering method which comprises: supporting a panel with its margins projecting and fabric thereon with the fabric marginal portions projecting beyond the panel; applying adhesive to the marginal portion of the fabric or panel; suctionally drawing the fabric edge-portions about and beneath the edge-portions of the panel; and pressing the fabric margins against the lower margin of the panel. 20
17. A panel-upholstering method which comprises: supporting a panel with its margins projecting and fabric thereon with the fabric marginal portions projecting beyond the panel; applying adhesive to the marginal portion of the fabric or panel; flexing the central portion of the panel away from the fabric; suctionally drawing the fabric edge-portions about and beneath the 30 edge-portions of the panel; and pressing the fabric margins against the panel.
18. A panel-upholstering method which comprises: supporting a panel-board with its margins projecting and a superposed fabric thereon 35 with its margins projecting beyond those of the panel-board and free from support; pneumatically folding the margins of the fabric about the edges of the panel-board and against the back thereof and interposing an adhesive; and bringing the margins of the panel-board and the underlying margins of the fabric under compressive action against an underlying bearing-surface.
19. In a machine of the character set forth: 45 a frame; a suction-box mounted on said frame and having an opening in its upper side and having a bearing-surface for the margins of a panel; an upwardly concave panel-support disposed over said opening and vertically reciprocable above 50 the plane of said suction-box and adapted to suctionally hold the panel and cause the margins to seat on said bearing; and means for effecting relative approaching and receding movements between said suction-box and panel-support. 55
20. A machine as specified in claim 19, in which said panel-support is tiltably mounted.
21. In combination: a suction-box having a top wall provided with an air-admission opening and provided also with a peripheral panel-bearing; a plunger working vertically through said suction-box and carrying at its upper end a suctional panel-support reciprocable through a 60 space above the plane of the top of said suction-box and adapted to carry a panel with projecting margins adapted to seat on said panel-bearing and a superposed panel-cover with margins projecting beyond the edges of the panel, whereby 70 the margins of the cover may be suctionally drawn about and beneath the margins of the panel; and mechanism for reciprocating said plunger.
22. A machine as specified in claim 21, in which 75

the mechanism for reciprocating said plunger comprises a motor-driven cam and an arm actuated thereby.

23. In combination: a frame having in its upper portion a suction-box provided with a suction-opening through its top wall and provided also with a peripheral bearing for a panel; a vertical plunger working through said suction-box; a suctional panel-support tiltably mounted on the upper end of said plunger and adapted to support a panel with projecting margins and a fabric with margins projecting beyond the edges of the panel; and power-driven mechanism for reciprocating said plunger.

24. A machine as specified in claim 23, combined with a panel-support tilting-device actuated in timed relation with respect to the reciprocation of said plunger.

25. In combination in a panel-upholstering machine: a frame having an upwardly presented peripheral bearing-surface against which the margins of a panel-board may seat; a panel-board support relatively movable with respect to said bearing-surface through a space above said bearing-surface and adapted to carry a panel-board with margins projecting beyond the edges of the panel-support in position to seat against said bearing-surface and a superposed fabric with margins projecting beyond the edges of the panel-board and free from support; and means for causing relative reciprocation between said panel-board support and said bearing-surface and for interposing the margins of said fabric between the margins of the panel-board and said bearing-surface in position to be clamped therebetween.

ALLISTER S. MITCHELL.
